UNITED STATES PATENT OFFICE

147,906

DESIGN FOR A GAME BOARD

George A. Inglis, Bayside, N. Y.

Application July 10, 1946, Serial No. 131,449

Term of patent 3½ years

(Cl. D34—5)

To all whom it may concern:

Be it known that I, George A. Inglis, a citizen of the United States of America, residing in Bayside, city of New York, county of Queens, and State of New York, have invented a new, original, and ornamental Design for a Game Board, of which the following is a specification, reference being had to the accompanying drawing, forming part thereof, in which Fig. 1 is a top plan view of a game board, showing my new design, and Fig. 2 is a side view of the same, all sides of the board being similar.

I claim:

The ornamental design for a game board, substantially as shown and described.

GEORGE A. INGLIS.
